UNITED STATES PATENT OFFICE.

ALANSON C. ESTABROOK, OF NORTHAMPTON, MASSACHUSETTS.

DESIGN FOR A BACK FOR BRUSHES.

SPECIFICATION forming part of Design No. 24,044, dated February 19, 1895.

Application filed July 14, 1894. Serial No. 517,610. Term of patent 14 years.

To all whom it may concern:

Be it known that I, ALANSON C. ESTABROOK, a citizen of the United States, residing at Northampton, in the county of Hampshire and State of Massachusetts, have invented and produced a new and original Design for Backs or Bodies of Brushes, Mirrors, and the Like, of which the following is a specification, reference being had therein to the accompanying drawings.

Figure 1 is a perspective illustrating my design. Fig. 2 is a view in cross-section on line 2—2 of Fig. 1.

The body or back A and the handle thereof are substantially in the outline of ellipses in

line with and merging into each other on graceful curves, the size of the handle being less than that of the back, as illustrated. The edge is ornamented by a raised or projecting rib or bead B.

What I claim is—

The design for a brush or mirror back or body, substantially as shown.

In testimony whereof I affix my signature in presence of two witnesses.

ALANSON C. ESTABROOK.
